(57) **CLAIM**

The ornamental design for a multi-position chair, as shown and described.

DESCRIPTION

FIG. 1 is a front perspective view of a first embodiment of the chair according to the instant invention;

FIG. 2 is a rear perspective view of the chair of FIG. 1;

FIG. 3 is a front elevational view of the chair of FIG. 1;

FIG. 4 is a rear elevational view of the chair of FIG. 1;

FIG. 5 is a side elevational view of the chair of FIG. 1;

FIG. 6 is a top view of the chair of FIG. 1;

FIG. 7 is a bottom view of the chair of FIG. 1;

FIG. 8 is a front perspective view of a second embodiment of the chair according to the instant invention;

FIG. 9 is a rear perspective view of the chair of FIG. 8;

FIG. 10 is a front elevational view of the chair of FIG. 8;

FIG. 11 is a rear elevational view of the chair of FIG. 8;

FIG. 12 is a side elevational view of the chair of FIG. 8;

FIG. 13 is a top view of the chair of FIG. 8;

FIG. 14 is a bottom view of the chair of FIG. 8;

FIG. 15 is a front perspective view of a third embodiment of the chair according to the instant invention;

FIG. 16 is a rear perspective view of the chair of FIG. 15;

FIG. 17 is a front elevational view of the chair of FIG. 15;

FIG. 18 is a rear elevational view of the chair of FIG. 15;

FIG. 19 is a side elevational view of the chair of FIG. 15;

FIG. 20 is a top view of the chair of FIG. 15; and,

FIG. 21 is a bottom view of the chair of FIG. 15.
